J. SCHMID

COMB CLEANER

Filed April 25, 1925

Inventor.
JACOB SCHMID
Victor J. Evans
attorney.

UNITED STATES PATENT OFFICE.

JACOB SCHMID, OF REDWOOD CITY, CALIFORNIA.

COMB CLEANER.

Application filed April 25, 1925. Serial No. 25,832.

This invention relates to improvements in comb cleaners, and has particular reference to a device for removing the dirt and grease from the side of the teeth of a comb.

5 The principal object of this invention is to produce a device which will automatically cause the comb to rise and fall as it is reciprocated along the wires of the cleaning device.

10 Another object is to produce a device of this character which is simple in construction and therefore cheap to manufacture.

A further object is to produce a device which will automatically maintain the wires 15 under any tension at all times.

A still further object is to produce a device wherein the cleaning wires are formed of one continuous wire.

Other objects and advantages will be apparent during the course of the following 20 description.

In the accompanying drawings forming a part of this specification, and in which like numerals designate like parts throughout 25 the same,

Fig. 1 is a perspective view of my improved comb cleaner,

Figure 2 is a perspective view of the wire carrying device,

30 Figure 3 is an enlarged detail end view, Figure 4 is a fragmentary detail view showing the manner of attaching the handle,

Figure 5 is a diagrammatic view showing the arrangement of the wires.

35 It is a well known fact that combs after having been passed through the hair, collect a considerable amount of lint which, taken with the natural oil of the hair is deposited upon the teeth of the comb, with the result 40 that the comb becomes dirty and unsanitary.

I have therefore provided a device which will effectively remove this deposit from the teeth of the comb in a minimum amount of time.

45 In the accompanying drawings wherein for the purpose of illustration is shown a preferred embodiment of my invention, the numeral 5 designates a handle which is attached as by a screw 6 to a Z-shaped supporting element 7. This supporting element has two parallel portions 8 and 9 which are grooved as shown at 11 and 12.

This element is preferably constructed of a resilient material so as to maintain the tension of the wire to be coiled thereon, as will be later described.

It will be noted that the grooves 11 are spaced further apart than the grooves 12, the reason for which is that when winding a wire upon the device one end is soldered as for instance the end 8, and wound through one of the grooves 11 to a corresponding groove in the end 9, thence around the end 9 and through one of the grooves 12 in that end, and thence to the corresponding groove 12 in the end 8. With the second convolution the wire is carried through the same groove 11 as the first wire but is carried through a new groove 12, with the result that convolutions of wire thus present 70 a plurality of single strands as shown at 13 upon one side of the device, and a plurality of double strands as shown at 14, upon the opposite side of the device. The numeral 15 indicates a covering of solder which is applied to the parallel portions 8 and 9 and serves not only to maintain the wires 14 in proper alignment but also functions to strengthen the device.

The manner of using my device is as follows:—

The comb is held in one hand and moved into contact with the device so that the teeth will straddle the wires. Assuming that the user is desirous of cleaning the coarse teeth, these teeth will straddle the wire 14, then with a back and forth motion, similar to that employed in filing, and by pressing slightly to either side of the teeth, the dirt will be scraped from the teeth, and by moving the comb the entire length of the device, it will be evident that the inclined portion of the Z-shaped member will act as a cam to raise and lower the comb, thereby cleaning the entire length of the teeth from base to tip. The fine teeth are cleaned in a similar manner with the exception that the wires 13 are employed.

It is to be understood that the form of my invention herewith shown and described is to be taken as a preferred embodiment of the same and that various changes relative to the size, shape and arrangement of parts may be resorted to without departing from

the spirit of the invention or the scope of the subjoined claim.

Having thus described my invention, I claim:—

5 In a device of the character described, a handle, a resilient Z-shaped supporting member having two substantially parallel

end portions, and a wire wound on said supporting member in such a manner as to produce a plurality of parallel strands, for the purpose specified.

In testimony whereof I affix my signature.

JACOB SCHMID.
